CLAIM

The ornamental design for a stand for bird feeder, as shown and described.

DESCRIPTION

FIG. 1 is a perspective view of the stand for bird feeder according to the present invention;

FIG. 2 is a front view of the stand for bird feeder according to the present invention;

FIG. 3 is a rear view of the stand for bird feeder according to the present invention;

FIG. 4 is a left side view of the stand for bird feeder according to the present invention;

FIG. 5 is a right side view of the stand for bird feeder according to the present invention;

FIG. 6 is a top view of the stand for bird feeder according to the present invention; and,

FIG. 7 is a bottom view of the stand for bird feeder according to the present invention.

The broken lines in all views are for illustrative purposes only and form no part of the claimed design.
